UNITED STATES PATENT OFFICE

CONSTANTIN FRIEDRICH RÖBER, OF DRESDEN, GERMANY, ASSIGNOR TO THE FIRM
"UNIVERSELLE" CIGARETTENMASCHINEN-FABRIK, J. C. MÜLLER & CO., OF DRESDEN, GERMANY

TRANSFERRING MEANS FOR CIGARETTE COUNTER-ROLLING MACHINES

Application filed August 24, 1925, Serial No. 52,048, and in Germany November 22, 1924.

This invention relates to cigarette making machines and particularly to a device thereof for providing cigarette sleeves with coiled paper mouth pieces.

5 When a coiled paper mouth piece is passed into the cigarette sleeve from a mandrel, the same has the tendency to uncoil in the cigarette sleeve in a non-uniform manner producing between the outer part of its winding and 10 the inner wall of the cigarette sleeve an objectionable gap. To avoid such gaps, the cigarette sleeve must be turned in a direction opposite to that of the winding of the coil. Formerly, this was done by hand but later a 15 special device, known as a counter-rolling device, was introduced whereby the uniform unwinding of the coil was produced automatically. To transfer the cigarette sleeve equipped with the coiled mouth piece into 20 the counter-rolling device, presents certain difficulties since the cigarette sleeve must enter the counter-rolling device in a certain position, to wit, parallel to the axle of the rapidly revolving roller thereof in order to 25 prevent it from being torn. The cigarette sleeve must therefore be properly guided and fed after it is removed from the mandrel, so as to be incapable of accidentally changing a certain position to which it was once adjusted. To this end a well-known device is 30 used which comprises a pair of guides forming between themselves a guide channel leading into the counter-rolling device and through which the cigarette sleeve is fed by 35 a push member.

It has been found that this device as hitherto used is objectionable because of the great precision required in the construction thereof.

According to the present invention the device is 40 considerably simplified and affords a more positive control of the pusher in feeding the cigarette sleeve through the guide channel.

My improved device is illustrated in the 45 accompanying drawing in which Fig. 1 is a side view and Fig. 2 a top plan view thereof.

The well-known counter-rolling device comprises a rapidly revolving roller 4 and a stationary cylindrically curved base plate 3 arranged concentrically to said roller and

forming between itself and the latter a channel 5 for the cigarette sleeve. The guide channel A through which the cigarette sleeve X is transferred to the counter-rolling device after its removal from the mandrel (not 55 shown) is formed by two vertically superposed substantially fork shaped members 1 and 2 of which the member 2 with one end is adapted to constantly bear on the inner end of the base plate 3 and the other end of which 60 embraces a stationary pin 2'. The second member 1 at its end remote from the counter rolling device embraces a stationary pin 1' and is acted upon by the spring s so connected to the plate 2 that the latter is caused to constantly bear against the base plate 3 and the member 1 is drawn toward the member 2. The spring s is extremely weak so that when the cigarette sleeve X is fed through the channel A it will overcome the tension of the 65 spring and raise the member 1. Working through the spaces between the forks of the members 1 and 2 is a forked member 6 which serves to feed the cigarette sleeve through the channel A into the channel 5 of the 70 counter-rolling device.

Thus far the construction is old.

The present invention resides in the particular mechanism or device for controlling the movement of the push member 6 so that 80 from the moment it engages the cigarette sleeve in the channel A it will continuously bear against the cigarette sleeve until the latter passes into the channel 5 or becomes engaged by the roller 4, whereby said sleeve will 85 be prevented from becoming accidentally displaced from its once adjusted position.

According to my invention the push member 6 is carried by a member 7 mounted on the end of a double armed lever 8 which 90 swings around a crank pin 9 provided on a crank disc mounted on a shaft 10 driven from a shaft 11 by means of gears 12 and 13.

The free end of the double arm lever 8 is 95 formed to a cylindrical rod 14 slidable longitudinally in a socket 15 which is carried by a pin 16. The pin 16 is rotatively borne in a bracket 17 in the free end of a rocking lever 17' the end of which is schematically shown in Fig. 2. When the lever 8 is rocked through 100

the medium of the crank pin 9 the end 14 will slide longitudinally in the socket 15 which will swing on its pin 16 as a result of which the push member 6 will describe a substantially elliptical path. Now then if the lever 17' is also rocked as a result a composite motion will be imparted to the push member 6 which will modify the path described by the member 6 under the influence of the motion 10 imparted to it by crank pin 9 alone. The elliptical path shown in dotted lines is the one resulting from the composite motion imparted, as evidenced by the full line and dotted line positions of the member 6, the 15 crank pin 9 and bolt 16 (Fig. 1). It is possible to increase considerably the path of the member 6 by the simple expedient of using the rock lever 17' and suitably rocking it.

The operation of the device is as follows:

20 The cigarette sleeve X equipped with the mouth piece coil (not shown) is passed from a mandrel m hereinbefore stated into the channel A by any suitable means so as to extend transversely therethrough, at the time 25 the push member 6 is at its left lower position (Fig. 1) about to enter the channel A from below the guide member 2. Owing to the action of the spring s, the guide member 1 will slightly press on the cigarette sleeve X 30 and prevent it from rolling. When the push member 6 projects into the channel during its upward stroke continuing its elliptical path it engages the cigarette sleeve X from the rear side thereby positioning it to be parallel to 35 the axis of the roller 4 and by pushing it forwardly feeds said sleeve parallel to itself until the latter passes into the channel 5 and is engaged by the rapidly revolving roller 4.

Thus, the control of the movement of the 40 sleeve X is positive throughout the length of the channel A or from the instant it is inserted into the latter until it reaches the channel 5.

What I claim is:—

45 1. In a device of the character described, the combination with a counter-rolling device and a cigarette sleeve receiving channel leading into said device, of a push member for feeding the cigarette sleeve from said channel into said counter-rolling device, a double armed lever carrying said push member, a crank pin on which said lever is fulcrumed, a turnable socket in which the free end of said lever is longitudinally slid able and a rocking lever carrying said socket.

2. The combination with a cigarette sleeve counter-rolling device, of means for transferring a cigarette sleeve to said counter-rolling device, comprising a pair of superposed guide members forming between themselves a channel leading into said counter-rolling device, said guide member being adapted to frictionally engage said cigarette sleeve, a push member for feeding said cigarette sleeve, through said channel into said

counter-rolling device and means for moving said push member in an elliptical path through said channel so as to constantly bear against said sleeve until the latter enters said counter-rolling device, said means including a double armed lever carrying said push member, crank driving means to which said lever is fulcrumed, a rotatable socket in which the free end of said lever is longitudinally slide able and a rocking lever carrying said socket.

3. In a device of the character described the combination with a counter rolling device and a cigarette sleeve receiving channel leading into said device of a push member for feeding the cigarette sleeve from said channel into said rolling device, a lever carrying said push member, crank driving means to which said lever is fulcrumed, a rotatable socket in which the free end of said lever is longitudinally slide able and means for changing the position of said socket.

In testimony whereof I affix my signature.
CONSTANTIN FRIEDRICH RÖBER.
